UNITED STATES PATENT OFFICE

2,165,866

ROOFING

Paul Logan, Chicago, Ill., assignor to The Logan-
Long Company, Chicago, Ill., a corporation of
Ohio

Application May 16, 1936, Serial No. 80,091

4 Claims. (Cl. 108—8)

My invention relates to roofing, and includes among its objects and advantages a material reduction in the cost of roofing of the type built up chiefly of felt and asphalt with or without a 5 grit surfacing; the utilization of waste material accumulating in the manufacture of such roofing; an expedient for preventing applicators from economizing too much on overlap; and the production of new designs. Further objects and 10 advantages of the invention will become apparent as the description proceeds.

The type of roofing common in the art and commonly referred to as flexible asphalt roofing has, in the past, practically always been built 15 up of a strip of felt impregnated with asphaltum, and then surfaced with a coat or layer of additional asphaltum, and then usually surfaced a second time with small pieces of slate or equivalent materials commonly referred to as grits. 20 After the production of a continuous strip of such material the strip has to be cut into smaller pieces. Even when these pieces are smaller strips of considerable length, commonly referred to as roll roofing, there is material waste in cutting 25 up the continuous strip, and the scraps accumulate. In many instances such a continuous strip is cut into individual shingles or strip shingles, and in such cases there is usually a materially greater amount of small pieces that are of no 30 use at all in the form in which they accumulate.

In roofing such as has just been described, the most expensive element or portion is the 35 felt. According to my invention it is possible, not only to utilize the clippings or waste accumulated in producing roofing according to the prior art, but roofing according to the present invention can be built up entirely from new raw materials utilizing no fibrous ingredients at all or materially cheaper forms of fibrous ingredient 40 than the felt required for roofing according to the prior art.

In the accompanying drawings:

Figure 1 is a diagram indicating the steps 45 in one process of producing roofing according to the invention;

Figure 2 is a sectional view as on line 2—2 of Figure 1;

Figure 3 is an end elevation of the forming die as on line 3—3 of Figure 1;

Figure 4 is a section of two overlapping shingles in such a position as they would occupy on a roof;

Figures 5, 6, 7, and 8 are similar cross sections illustrating variations in shingle shapes;

Figure 9 is a diagram of one way of laying shingles according to Figure 8; and

Figure 10 is a diagram of one way of laying shingles according to Figure 7.

In the embodiment of the invention indicated in Figure 1, 10 is a rotary kiln having any suitable drive means indicated at 12, and heating means indicated as a burner at 14. Into this kiln the ingredients for the mix are charged. Scrap from the manufacture of ordinary roofing, 10 including such grits as may be sticking to the scrap, forms a satisfactory charge in nearly every instance, but may, if desired, be supplemented by additional materials to secure any desired proportion of ingredients that may happen to differ slightly from the composition of the scrap. In using other raw materials the kiln may be charged with asphaltum, plastic wood, or equivalent mastic materials, which may be supplemented by fillers such as powdered clay, dolomite or the like, or by fibrous fillers, or by both. The fibrous fillers may include asbestos fibre, but for most grades I can use the type of fibre from which ordinary roofing felt is made. This eliminates the expense of making the fibre up into felt. It is also possible to use cheaper grades of fibre with entirely satisfactory results.

The charge in the kiln is heated until it becomes a plastic or viscous mass, but it is not always convenient to operate the kiln so that a satisfactorily complete mixing takes place in the kiln. 16 indicates a mixer into which heated material from the kiln is charged. I have indicated a discharge spout 18 for continuous charging to enhance the clearness of the drawings. In the mixer 16 the plastic or viscous mass is agitated as by paddles 20 enough to produce a satisfactory degree of homogeneity or uniformity in the mix. The mixed material is then transferred to an extrusion device for forming a continuous strip therefrom. I have indicated a continuous discharge from the mixer by means of the spout 22, and an extrusion device including the housing 24, the worm 26, and the die 28. The die 28 is shaped to deliver a strip having the complete cross section of a finished shingle, and with ingredients such as I have described, it is possible to produce such shingles having superior strength characteristics without any underlying felt support at all.

The strip leaving the die 28 is substantially solid. When it is to be used with a grit surfacing, I reheat the entire strip, or at least the portion destined to receive the grits. I have indicated guiding rolls 30 for conveying the strip to a re-

heat kiln 32. The kiln illustrated comprises a housing 34 of refractory material having the shape of an inverted U, and overlying the strip 36. In the illustrative embodiment of Figure 2, 5 the top and right hand walls of the kiln are strongly heated as by a flame 38 issuing from a burner 40. Particularly when the strip 36 has irregularities in its upper surface, I may preserve the shape of such irregularities by positioning the strip as clearly indicated in Figure 2 so that the portion of the upper surface having the irregularity is not directly exposed to the radiant heat 10 in the kiln but substantially shielded therefrom by the lower edge of the left hand wall of the kiln. In this way the heating action may be localized over that portion of the surface to which the grits are to be applied, and that portion of the surface may be heated to incipient fusion or to build up a very thin surface layer of entirely 15 molten material.

Immediately upon issuing from the kiln 32 the strip receives suitable grits 42 from a hopper 44, and then passes through rollers 46 which press the grits into the asphalt, and cutting rolls 48 25 which cut the strip transversely. It will be obvious that these rolls may notch the edge of the strip and make complete transverse cuts between the notches so as to form the well known form of strip shingles, or that all the transverse cuts may sever the strip completely, thereby forming individual shingle pieces. Any of the designs known to the prior art can be produced with equal facility by the rolls 48.

The forming process just described facilitates the formation without any waste whatever of any desired predetermined cross section. Referring to Figure 4 I have illustrated shingles 50 of substantially plain rectangular cross section except for a slight taper in the upper half of the shingle. It will be noted that when such shingles 50 are laid, there will be spaces between the shingle and the supporting roof boards, as indicated at 52 in Figure 4. Figure 5 indicates a shape that can be produced with equal facility. The exposed surface in Figure 5 is identical with that in Figure 4, 45 but the space 52 has been filled in solid by merely changing the shape of the die so that the lower surface of the shingle has a shoulder at 54 having a height equal to the height of the upper edge 50 of the underlying shingle.

In Figure 6 I have indicated a shingle shaped with a downwardly facing shoulder at 56 formed on the upper face of the underlying shingle near its upper edge. The lower edge of the overlying shingle is formed with a complementary shape so 55 that the assembled shingles not only interlock but fit together without any air spaces or pockets anywhere.

The shape of the shingles of Figure 7 differs 60 from that in Figure 6 in that all the shoulders are inclined downwardly at a suitable angle, which I have indicated as 45°. Thus the shoulder 58 has a decided hook shape which renders the interlock somewhat more effective.

In Figure 8 I have indicated the ease with 65 which shingles with the same type of interlock as in Figure 7 can be designed to lay a roof of two or more thicknesses by merely moving the shoulders 78 to the position illustrated and 70 shaping the under surface of the overlying shingle to correspond. I have also indicated the exposed lower edges of the shingles beveled as at 80 at such an angle that they can receive and retain grits. A finished roof of shingles according to 75 Figure 8, accordingly, will present to the eye a

continuous surface of grits, without the sharp discontinuities formed by the lower edges of shingles according to Figure 7.

The conditions attending manufacture of roofing according to the prior art have been such that users have become accustomed to regarding a heavy shadow line as indicating a superior product. It will be noted that the lower edges of any of the shingles of Figures 4 to 8 may be made of any desired thickness, and may terminate at any 10 desired angle, and may be surfaced with grits or left uncovered and additionally conspicuous by reason of the dark color of the mastic. In Figure 9 I have shown a plan view of a portion of a roof employing shingles according to Figure 8. It will be noted that the shingle 82 extends up behind the lower edges of the second course of shingles above. Such a roof is complete in itself and can be laid over new roof boards or over old roofing.

Shingles according to Figure 7 can also be 20 laid in the same way, but only over roll roofing or some other means for stopping the cracks between adjacent shingles in the same course. However, a Dutch lap roof complete in itself can advantageously be laid with shingles according 25 to Figure 7. In Figure 10, the shingle 84 has its hook-shaped portion 58 located as indicated, and its right edge terminates at 60. A single fastening only is shown at 86. The dotted line at 88 indicates the lower edge of the next course of 30 shingles, which can be laid with their vertical joints in any desired relationship to the joints in the course below. The nails applied to fasten down the lower edge of each course will also penetrate the upper edge of the course below.

Without further elaboration, the foregoing will 35 so fully explain my invention that others may, by applying knowledge current at the time of application, readily adapt the same for use under various conditions of service. It will be apparent that any material which can be called mastic, in the sense that it is capable of changing from a state or condition capable of being rolled or shaped by plastic deformation, into a condition 40 of greater strength or rigidity, as by cooling or 45 by chemical action, can be processed according to the present invention.

I claim:

1. A roof comprising, in combination: a supporting roof structure; overlapped shingles on said structure; each shingle being composed of a body of mastic material; an upper edge portion of each shingle underlying a lower portion of an adjacent second shingle higher up and extending under said second shingle to a point below a lower edge 55 portion of a third shingle still higher up; said first mentioned shingle having an upper surface sloping gently toward the plane of said supporting roof structure; said sloping surface having a single downwardly facing shoulder approximately midway between the upper edge of said first shingle and the lower edge of said second shingle; the under surface of said second shingle having an upwardly facing shoulder fitting into said downwardly facing shoulder; said shoulders 60 being hook-shaped, whereby the second shingle is held down by inter-engagement of said shoulders; the upper edge of said first mentioned shingle being beveled with its sharper edge next the bottom; said second shingle having its under 65 surface shouldered to fit said edge; all said shingles being of identical cross section and fitting together without distortion of the mastic material into a substantially solid mass without air pockets; the lower edges of said shingles being 70

75

beveled with their sharper edges next the bottom; the exposed surface portion and the beveled lower edge of each shingle being substantially covered with weather-resistant granular material embedded in the mastic material; said shingles being of uniform cross section from side to side.

2. A roof comprising, in combination: a supporting roof structure; overlapped shingles on said structure; each shingle being composed of a body of mastic material; an upper edge portion of one shingle underlying a lower portion of an adjacent second shingle higher up; the upper surface of said first mentioned shingle having a downwardly facing shoulder; the under surface 10 of said second shingle having an upwardly facing shoulder fitting into said downwardly facing shoulder; said shoulders being hook-shaped, whereby the second shingle is held down by inter-engagement of said shoulders.

20 3. A roof comprising, in combination: a supporting roof structure; overlapped shingles on said structure; each shingle being composed of a body of mastic material; an upper edge portion of each shingle underlying a lower portion of an adjacent second shingle higher up; said first mentioned shingle having an upper surface sloping gently toward the plane of the supporting roof structure; said sloping surface having a single downwardly facing shoulder approximately midway 25 30 way between the upper edge of said first shingle and the lower edge of said second shingle; the under surface of said second shingle having an upwardly facing shoulder fitting into said down-

wardly facing shoulder; said shoulders being hook-shaped, whereby the second shingle is held down by inter-engagement of said shoulders; said second shingle having its under surface shouldered to fit the upper edge of said first mentioned shingle; all said shingles being of identical cross section and fitting together without distortion of the mastic material into a substantially solid mass without air pockets.

4. A roof comprising, in combination: a supporting roof structure; overlapped shingles on said structure; each shingle being composed of a body of mastic material; an upper edge portion of each shingle underlying a lower portion of an adjacent second shingle higher up; said first mentioned shingle having a single downwardly facing shoulder approximately midway between the upper edge of said first shingle and the lower edge of said second shingle; the under surface of said second shingle having an upwardly facing shoulder fitting into said downwardly facing shoulder; said shoulders being hook-shaped, whereby the second shingle is held down by interengagement of said shoulders; the upper edge of said first mentioned shingle being 20 beveled with its sharper edge next the bottom; said second shingle having its under surface shouldered to fit said edge; said edge engagement and the engagement of said hook-shaped shoulders being on faces lying in substantially parallel planes.

PAUL LOGAN.
